ABSTRACT OF THE DISCLOSURE

A synergistic anti-foaming composition consisting of a mixture of (a) a reaction product of ethylenediamine with ethylene oxide and propylene oxide in any sequence, having a turbidity point of from 10° C. to 35° C., and (b) a fatty component selected from the group consisting of fatty alcohols having 12 to 18 carbon atoms and water-insoluble reaction products thereof with ethylene oxide; said components (a) and (b) being present in a proportion by weight selected from the group consisting of 5:1 to 20:1 and 1:5 to 1:20, as well as aqueous cleaning compositions containing from 0.1 to 1 gm. per liter of said anti-foaming composition.

THE PRIOR ART

In many cases it is desirable for the aqueous solutions of cleaning compositions to have a strong cleaning action and a low foaming power. For a long time, therefore, poorly foaming wetting agents especially nonionic wetting agents have been used, provided that the cleaning effect is sufficient. However, it is often still necessary to use additional anti-foaming compositions. This applies particularly to the industrial cleaning of rigid surfaces such as metal, glass and ceramics in automatic cleaning plants. In the cleaning of bottles especially, very large throughputs take place within short periods, and development tends increasingly to shorten the treatment time. The demands on the cleaning power of the solutions are constantly increased simultaneously with the demands on the anti-foaming substances, since the baths readily tend to form foam, not only from the ingredients therein but especially through the impurities which have been introduced into the cleaning bath. The best cleaning action, however, cannot be used in practice if, at the same time, the development of foam has not been sufficiently suppressed. Therefore, it is in many cases desirable to improve further the anti-foaming action.

OBJECTS OF THE INVENTION

An object of the invention is to develop an anti-foaming composition which is stable in strongly alkaline solutions and suppresses foam in the use of cleaning baths.

Another object of the invention is to develop a synergistic anti-foaming composition consisting of a mixture of (a) a reaction product of ethylenediamine with ethylene oxide and propylene oxide in any sequence, having a turbidity point of from 10° C. to 35° C., and (b) a fatty component selected from the group consisting of fatty alcohols having 12 to 18 carbon atoms and water-insoluble reaction products thereof with ethylene oxide;

2

said components (a) and (b) being present in a proportion by weight selected from the group consisting of 5:1 to 20:1 and 1:5 to 1:20.

A further object of the invention is to develop an aqueous cleaning composition containing customary washing ingredients and from 0.1 to 1 gm. per liter of a synergistic anti-foaming composition consisting of a mixture of (a) a reaction product of ethylenediamine with ethylene oxide and propylene oxide in any sequence, having a turbidity point of from 10° C. to 35° C., and (b) a fatty component selected from the group consisting of fatty alcohols having 12 to 18 carbon atoms and water-insoluble reaction products thereof with ethylene oxide; said components (a) and (b) being present in a proportion by weight selected from the group consisting of 5:1 to 20:1 and 1:5 to 1:20.

A yet further object of the invention is the development of a method for suppressing foam in strongly foaming aqueous cleaning compositions which comprises agitating a strongly foaming aqueous cleaning composition and adding thereto from 0.1 to 1 gm. per liter of a synergistic anti-foaming composition consisting of a mixture of (a) a reaction product of ethylenediamine with ethylene oxide and propylene oxide in any sequence, having a turbidity point of from 10° C. to 35° C., and (b) a fatty component selected from the group consisting of fatty alcohols having 12 to 18 carbon atoms and water-insoluble reaction products thereof with ethylene oxide; said components (a) and (b) being present in a proportion by weight selected from the group consisting of 5:1 to 20:1 and 1:5 to 1:20.

These and other objects of the invention will become more apparent as the description thereof proceeds.

DESCRIPTION OF THE INVENTION

The present invention provides synergistic foam-inhibiting additives and a cleaning composition having said foam-inhibiting additives, comprising an anti-foaming composition a mixture of

(a) A reaction product of ethylenediamine with ethylene oxide and propylene oxide in any sequence, and which has a turbidity point in the region of 10° to 35° C., and

(b) A fatty alcohol having 1 to 18 carbon atoms or water-insoluble reaction product thereof with ethylene oxide, wherein the said components (a) and (b) are present in a proportion by weight of 5:1 to 20:1, or 1:5 to 1:20, respectively.

In the utilization of the reaction products of the ethylenediamine with ethylene oxide and propylene oxide or propylene oxide and ethylene oxide, it is essential for the turbidity point to lie within the indicated range. Preferably, the turbidity point should lie within the range of 15° to 32° C. The respective turbidity point is found by slowly heating a 1% solution of the compound in question and observing the first easily optically recognizable turbidity. The turbidity points indicated relate to pure solutions of the substances in question. The turbidity point is altered by the addition of other foreign substances.

In the following table the turbidity points of some characteristic compounds are given. The abbreviations EO for ethylene oxide and PO for propylene oxide have been used. The statement "ethylenediamine +30 EO +60 PO" means that 30 mols of ethylene oxide and after this 60 mols of propylene oxide have been added on per mol of ethylenediamine. Since the addition takes place statisti-

cally, there are also formed, to a certain extent, compounds in which the indicated number of molecules of ethylene oxide and propylene oxide is somewhat lower or somewhat higher, so that the given formulation represent the average value.

TABLE A

	Ratio EO:PO	Turbidity range in °C.
Ethylene diamine+30 EO+60 PO	1:2	20-30
Ethylenediamine+30 EO+87 PO	1:3	17-23
Ethylenediamine+30 EO+118 PO	1:4	14-19
Ethylenediamine+40 EO+78 PO	1:2	22-35
Ethylenediamine+40 EO+102 PO	1:2.5	17-25
Ethylenediamine+40 EO+128 PO	1:3	16-24
Ethylenediamine+46 EO+99 PO	1:2	18-29
Ethylenediamine+46 EO+131 PO	1:3	15-22
	Ratio PO:EO	
Ethylenediamine+52 PO+8 EO	6.5:1	19-28
Ethylenediamine+52 PO+18 EO	3:1	25-32

It can be seen from the table that, in order to attain the given turbidity point, generally the ratio of ethylene oxide: propylene oxide lies in the range of 1:2 to 1:4 and the ratio of propylene oxide: ethylene oxide lies in the range of 3:1 to 6.5:1. In the given ratios, in each case the alkylene oxide first mentioned is that which was added on first.

Certain gradual differences exist in the case of the individual products. A reaction product of ethylenediamine with about 30 mols of ethylene oxide and about 60 mols of propylene oxide has proved especially suitable.

Suitable fatty alcohols are especially dodecyl, tetradecyl, hexadecyl, octadecyl and oleyl alcohols. The water-insoluble products of ethylene oxide with the said fatty alcohols contain in general not more than 4 mols, preferably 1 to 2 mols, of ethylene oxide per mol of fatty alcohol. Generically, the second component of the synergistic anti-foaming composition of the invention is a water-insoluble compound having the formula

wherein R is a fatty radical having from 12 to 18 carbon atoms selected from the group consisting of alkyl, alkenyl and alkadienyl, and n is an integer from 0 to 4, preferably from 0 to 2. The reaction product of oleyl alcohol with 2 mols of ethylene oxide has proved especially suitable.

In order to attain an increased anti-foaming effect it is essential for the reaction products of the ethylenediamine and ethylene oxide and propylene oxide or propylene oxide and ethylene oxide on the one hand, and fatty alcohols or their water-insoluble reaction products with ethylene oxide on the other hand to be present in the given relative proportions of 5:1 to 20:1 and 1:5 to 1:20 respectively. A synergistic effect is in fact only obtained in the given ranges. It varies from case to case whether the fatty alcohols or their derivatives or the derivatives of the ethylenediamine should be present in excess. If this is not individually indicated in the present application, it can easily be found by a simple experiment. To some case, a synergistic effect occurs with an excess of either one or the other anti-foaming composition. In the other ranges, especially when there are equal parts of the two anti-foaming compositions, no synergistic or even a negative effect is obtained.

Preferred for the anti-foaming compositions of the invention are mixtures of (a) a reaction product of ethylenediamine with about 30 mols of ethylene oxide and about 60 mols of propylene oxide and (b) a reaction product of oleyl alcohol with 2 mols of ethylene oxide, in a weight ratio of 18:1 to 5:1. When fatty alcohols are employed as component (b) it is usually preferable to utilize them in excess in a weight ratio of component (a) to component (b) of 1:5 to 1:18.

The cleaning compositions may contain the usual wetting agent components, especially anionic wetting agents, particularly the sulfates and sulfonates, such as alkyl sulfates, alkyl sulfonates, alkylbenzene sulfonates and non-ionic wetting agents such as the polyglycol ethers, which are obtained by addition of ethylene oxide to fatty alcohols, fatty amines and carboxylic acid amides. Other customary washing compounds are suitable, for example builders and complex-formers such as orthophosphates, 10 polymeric phosphates, silicates, soda ash, potash, glucosates and other complex-forming compounds known as themselves as cleaning substances, such as nitrilo-triacetic acid, ethylenediaminetetraacetic acid or 1-hydroxy-alkane-1,1-diphosphonic acids. The compositions may further contain caustic alkalis such as caustic potash and caustic soda in considerable amounts, especially when they are used for cleaning bottles.

The said substances may be present in the cleaning compositions in the usual concentrations. The concentration of the anti-foaming agent mixture amounts to 0.1 to 1 gm. per liter, based on the solution used.

The new anti-foaming compositions have the advantage of a further reduced foam formation together with a stability against alkalis which, especially in the case 25 of industrial cleaners and preferably bottle cleaning compositions, enables the throughput in automatic cleaning machines to be further increased or the cleaning times to be shortened. The synergistic effect in the reduction of foaming, which is obtained with the very specific relative 30 proportions of the components to be used, was not to be foreseen, all the more so as no effects or negative results occurred with other mixing ratios.

The present invention will be further described with reference to the following specific examples which are not 35 to be deemed limitative.

Example 1

In a commercial bottle cleaning plant with an alkaline 40 zone, the hourly output of which amounts to 8000 bottles, and a temperature of 65° C., milk bottles were cleaned with a bottle cleaning mixture having the following composition on a dry basis:

45 85% sodium hydroxide
10% sodium tripolyphosphate
2% sodium silicate (molar ratio Na₂O:SiO₂=3.35)
3% anti-foaming mixture comprising (a) reaction product
50 of ethylenediamine with 30 mols of ethylene oxide and
60 mols of propylene oxide and (b) reaction product of
oleyl alcohol with 2 mols of ethylene oxide, in the proportions of 9:1.

The concentration of the cleaning solution was 1%. There 55 was a good cleaning action and no development of foam.

Example 2

In a bottle cleaning machine with 2 immersion baths and an hourly output of 10,000 units, beer and lemonade bottles were cleaned at a treatment temperature of 70° C. 60 The bottle cleaning mixture had the following compositions on a dry basis:

40% finely powdered sodium hydroxide
20% sodium tripolyphosphate
65 35% sodium sulfate
5% anti-foaming agent mixture comprising (a) reaction product of ethylenediamine with 30 mols of ethylene oxide and 60 mols of propylene oxide and (b) reaction product of oleyl alcohol with 2 mols of ethylene oxide, in the relative proportions of 5:1.

The bottles were provided with paper labels, which usually lead to strong foaming in the plant. When a concentration of 1.5% of the above-mentioned bottle cleaning composition was used, the plant operated for over a week without any tiresome development of foam.

Example 3

In a bottle cleaning plant with 3 separate alkaline baths and an hourly output of 24,000 units, wine bottles were cleaned at a temperature of 65° C. A 1% sodium hydroxide solution was used as a cleaning solution, to which was added 1.5 kg. of a cleaning agent concentrate per cubic meter with the following composition:

80% polymer phosphate (sodium salt)

20% anti-foaming agent mixture comprising (a) reaction product of ethylenediamine with 30 mols of ethylene oxide and 60 mols of propylene oxide and (b) reaction product of oleyl alcohol with 2 mols of ethylene oxide, in the ratio of 18:1.

The cleaning was satisfactory with only a small development of foam.

Example 4

For the preparation of a degreasing bath for steel parts a metal cleaning mixture of the following composition, on the dry basis, was used:

75% sodium hydroxide

19% trisodium phosphate

3% sodium tripolyphosphate

2% dodecylbenzenesulfonate (Na salt)

1% anti-foaming agent mixture comprising (a) reaction product of ethylenediamine with 30 mols of ethylene oxide and 60 mols of propylene oxide and (b) stearyl alcohol, in the ratio of 1:5.

The bath concentration was 5% and the treatment temperature 80° C. The very greasy steel parts were cleaned in 15 seconds. In spite of the high content of strongly-foaming fatty impurities introduced, no development of foam occurred.

Example 5

Machine finished parts were treated in a one-chamber spraying apparatus with a neutral liquid cleaning mixture of the following composition:

15% dodecylbenzenesulfonate (Na salt)

5% reaction product of nonyl phenol with 9 mols of ethylene oxide and 5 mols of propylene oxide

10% anti-foaming agent mixture comprising (a) reaction product of ethylenediamine with 52 mols of propyl-

ene oxide and 8 mols of ethylene oxide and (b) dodecyl alcohol, in the relative proportions of 1:5. 70% water

The concentration of the cleaning composition used was 5% and the spraying temperature was 40° C. In spite of the spray pressure of 1.5 atm., no objectionable foam development resulted.

Example 6

For the cleaning of work clothes in a commercial washing machine, a cleaning mixture of the following composition was used:

30% sodium tripolyphosphate

15% sodium perborate

10% sodium silicate (molar ratio Na₂O:SiO₂=3.3)

10% dodecylbenzenesulfonate (Na salt)

25% sodium sulfate

10% anti-foaming agent mixture comprising (a) reaction product of ethylenediamine with 46 mols of ethylene oxide and 131 mols of propylene oxide and (b) reaction product of oleyl alcohol with 2 mols of ethylene oxide, in the ratio of 5:1.

The concentration of the cleaning composition used was 0.5%. A satisfactory cleaning result could be obtained in the washing machine without any troublesome development of foam.

Example 7

In order to test the anti-foaming action, test solutions 30 were prepared which contained different amounts (given in p.p.m.) of tetrapropylenebenzenesulfonate in the form of the triethanolamine salt as the foam-producing agent tested.

The churning apparatus according to DIN 53903 was 35 used as the test apparatus. In the following tables the results of the tests are given in cc. of foam which were obtained under the different conditions with the anti-foaming compositions indicated in each case. In the left hand column the amount of foamer tested is noted, then 40 the foam numbers without anti-foaming composition and after that the results with addition of the anti-foaming composition alone and in various mixing proportions (given in p.p.m.). The individual components are denoted by I and II and correspond to the data at the top of the 45 table. The notations "EO" for ethylene oxide and "PO" for propylene oxide were used as previously defined. Ocenol is a commercial oleyl alcohol.

The preceding specific embodiments are illustrative of the practice of the invention. It is to be understood, however, that other expedients known to those skilled in the art may be employed without departing from the spirit of the invention or the scope of the appended claims.

We claim:

1. A synergistic anti-foaming composition consisting of a mixture of (a) an oxyalkylation reaction product of ethylenediamine with ethylene oxide and propylene oxide in any sequence, where, when the ethylene oxide is reacted first, the ethylene oxide: propylene oxide ratio is from 1:2 to 1:4 and when propylene oxide is reacted first, the propylene oxide: ethylene oxide ratio is from 3:1 to 6.5:1, said oxyalkylation reaction product having a turbidity point of from 15° C. to 32° C., and (b) a water-insoluble fatty component having the formula

wherein R is a fatty radical having 12 to 18 carbon atoms selected from the group consisting of alkyl, alkenyl and alkadienyl and n is an integer from 0 to 2; said components (a) and (b) being present in a proportion by weight of 5:1 to 20:1.

2. The composition of claim 1 wherein component (a) is the reaction product of ethylenediamine with about 30 mols of ethylene oxide and about 60 mols of propylene oxide and component (b) is the reaction product of oleyl alcohol with 2 mols of ethylene oxide.

3. The composition of claim 1 having from 5 to 18 parts by weight of the reaction product of ethylenediamine with about 30 mols of ethylene oxide and about 60 mols of propylene oxide as component (a) and 1 part by weight of the reaction product of oleyl alcohol with 2 mols of ethylene oxide as component (b).

4. An aqueous cleaning composition containing customary washing ingredients selected from the group consisting of anionic sulfate wetting agents, anionic sulfonate wetting agents, non-ionic wetting agents, builders and complex-formers, and caustic alkalis and from 0.1 to 1 gm. per liter of a synergistic anti-foaming composition consisting of a mixture of (a) an oxyalkylation reaction product of ethylenediamine with ethylene oxide and propylene oxide in any sequence, where, when ethylene oxide is reacted first, the ethylene oxide: propylene oxide ratio is from 1:2 to 1:4 and when propylene oxide is reacted first, the propylene oxide: ethylene oxide ratio is from 3:1 to 6.5:1, said oxyalkylation reaction product having a turbidity point of from 15° C. to 32° C., and (b) a fatty component having the formula

wherein R is a fatty radical having 12 to 18 carbon atoms selected from the group consisting of alkyl, alkenyl and alkadienyl and n is an integer from 0 to 2; said components (a) and (b) being present in a proportion by weight of 5:1 to 20:1.

5. The aqueous cleaning composition of claim 4 wherein component (a) is the reaction product of ethylenediamine with about 30 mols of ethylene oxide and about

60 mols of propylene oxide and component (b) is the reaction product of oleyl alcohol with 2 mols of ethylene oxide.

20 6. The aqueous cleaning composition of claim 4 wherein said anti-foaming composition contains from 5 to 18 parts by weight of the reaction product of ethylenediamine with about 30 mols of ethylene oxide and about 60 mols of propylene oxide as component (a) and 25 1 part by weight of the reaction product of oleyl alcohol with 2 mols of ethylene oxide as component (b).

7. A synergistic anti-foaming composition consisting of a mixture of (a) an oxyalkylation reaction product of 30 ethylene diamine with about 30 mols of ethylene oxide and about 60 mols of propylene oxide, having a turbidity point of from 20° C. to 30° C., and (b) a fatty component having the formula

35 wherein R is a fatty radical having 12 to 18 carbon atoms selected from the group consisting of alkyl, alkenyl and alkadienyl and n is an integer from 0 to 2; said components (a) and (b) being present in a proportion 1:5 to 1:20.

40 8. A synergistic anti-foaming composition consisting of a mixture of (a) an oxyalkylation reaction product of ethylenediamine with ethylene oxide and propylene oxide in any sequence, where, when ethylene oxide is reacted first, the ethylene oxide: propylene oxide ratio is from 1:2 to 1:4 and when propylene oxide is reacted first, the propylene oxide: ethylene oxide ratio is from 3:1 to 6.5:1, said oxyalkylation reaction product having a turbidity point of from 15° C. to 32° C., and (b) a water-insoluble fatty component having the formula

45 wherein R is a fatty radical having 12 to 18 carbon atoms selected from the group consisting of alkyl, alkenyl and alkadienyl and n is an integer from 0 to 2 said components (a) and (b) being present in a proportion by weight of 1:5 to 1:20.

50 9. The composition of claim 8 wherein component (a) is the reaction product of ethylenediamine with about 30 mols of ethylene oxide and about 60 mols of propylene oxide and in components (b), n is 0 and said components (a) and (b) are present in a proportion of 1:5 to 1:18.

10. An aqueous cleaning composition containing customary washing ingredients selected from the group consisting of anionic sulfate wetting agents, anionic sulfonate wetting agents, non-ionic wetting agents, builders and complexformers, and caustic alkalis and from 0.1 to 1 gm. per liter of a synergistic anti-foaming composition consisting of a mixture of (a) an oxyalkylation reaction product of ethylenediamine with ethylene oxide and propylene oxide in any sequence, where, when ethylene oxide is reacted first, the ethylene oxide: propylene oxide ratio is from 1:2 to 1:4 and when propylene oxide is reacted first, the propylene oxide: ethylene oxide ratio is from 3:1 to 6.5:1, said oxyalkylation reaction product

11

having a turbidity of from 15° to 32° C., and (b) a fatty component having the formula

wherein R is a fatty radical having 12 to 18 carbon atoms selected from the group consisting of alkyl, alkenyl and alkadienyl and n is an integer from 0 to 2; said components (a) and (b) being present in a proportion of 1:5 to 1:20.
